UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 13,380, dated October 31, 1882.

Application filed August 11, 1882. Term of patent 3½ years.

To all whom it may concern:

Be it known that I, WINTHROP L. JACOBS, of East Orange, in the State of New Jersey, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

A plain field is irregularly traversed by a net-work of short angular stems having nu-

merous small figures of various shapes, mostly 15 circular gems and small leaf forms, with here and there a larger star-shaped flower figure. These small figures are thickly strewn over the face of the design, so thickly as in some cases to overlie one another and give a warm effect 20 to the design as a whole.

I claim—

The design for carpets, substantially as shown and described.

WINTHROP L. JACOBS.
